UNITED STATES PATENT OFFICE.

THOMAS T. HOLLINGER, OF DETROIT, MICHIGAN.

INLAID LINOLEUM.

No. 884,732.

Specification of Letters Patent.

Patented April 14, 1908.

Application filed February 15, 1906. Serial No. 301,286.

To all whom it may concern:

Be it known that I, THOMAS T. HOLLINGER, a citizen of the United States, residing at Detroit, county of Wayne, State of Michigan, have invented a certain new and useful Improvement in Inlaid Linoleum; and I declare the following to be a full, clear, and exact description of the same, such as will enable others skilled in the art to which it pertains to make and use the same, reference being had to the accompanying drawings, which form a part of this specification.

This invention relates to floor coverings; it has for its object an improved plastic material in similar character to what is popularly known as linoleum, and which may be used either for floor coverings or wall coverings, as may be desired.

The special object of the invention is to produce such a material in a combination of colors, so arranged that the color scheme presents a pictorial effect, especially an effect which represents the surface or grain of wood, and with the colors so arranged that each color forms a part of the composite material, and extends back from the surface so that in effect the one color is inlaid with the other. Generally, there is a body color, which is first laid upon the canvas backing of the linoleum, and this is interpenetrated by thin masses of a different color laid into deep cuts or cavities in the mass having the body color, and this produces the desired configuration upon the surface of the completed material, and the configuration is permanent and not destroyed by use.

In the drawing:—Figure 1, is a perspective showing the appearance of a completed piece of the material. Fig. 2, is a cross section showing or indicating the arrangement of the two colors of material back from the surface.

The facing material, which is generally of a composition of an oxidized oil and cork quite finely ground, or some similar material is pressed strongly and heavily against a canvas back 1, making an even coating of the plastic material 2, of the surface thereof. Into this plastic surface, while it is still in a green state, are made deep incisions extending as nearly as is practicable to the canvas backing; these incisions 3 are made in short cuts and are arranged with reference to one another to produce on the surface of the material a wavy appearance, characteristic of what is known as the "grain" of wood. If a

careful examination of the grain of wood be made, it will be found that it has in nearly every instance, the appearance of short slightly sunken lines of a dark color in a surface of ground color that is not so dark. The general direction of these lines is lengthwise of the original log from which the lumber is cut, but owing to the irregularities in the growth of the timber the surface of lumber presents the grain lines in aggregations that are more or less wavy or irregular, but it will be found that in a given kind of wood, the length of each individual line is quite well defined, and while in any piece of wood there may be brought close together a number of these grain lines of varying length, it will be found that they have great regularity, that in their general characters they lie substantially parallel to what may be considered the axis of the log, and that the feature which characterizes most wood, and which appears at a distance as wavy lines running across the surface, is in reality aggregations of short lines, each of which runs lengthwise of the surface, but which are so disposed as to produce the general wavy character of the lines indicated in Fig. 1. The length of these lines differ in different varieties of wood, and in some varieties of wood, the lines are replaced by small specks or spots with interspersed lines arranged in the same way. Either feature may be copied in the inlaying process by which the result of this invention is produced, that is, I may prepare the body of the material by cutting into it short slits, whose axes are substantially parallel to the axis of the timber, or I may pierce the material with irregular holes aggregated to produce the same general result, or I may use both small irregular holes and slits. In any case, I copy a specific character of wood, and produce an appearance similar to the model that I have used. These short slits or other apertures are filled while the material is in a green uncured condition, with material similar in character but colored with a pigment of a color to produce the desired effect. For instance, to produce the effect of red oak, the foundation material should be of a buff verging onto yellow, and the lists should be about half an inch long, or varying perhaps between three-eighths and two-thirds of an inch, and these slits should be filled with material similar in character to that of the foundation, but of the proper color to produce the desired result. After the material is cured,

the two substances coalesce and form a solid homogeneous mass in which the filling material runs so deeply into the foundation material that it is practically as indestructible as 5 the foundation itself.

What I claim is:—

1. A covering material having in combination a fabric base, a plastic coating laid directly thereon, said coating having a plurality of small lines deeply indented in its exposed surface, and material homogeneous with said coating but of different color, inlaid in said small lines, substantially as described. 10
2. As a new article of manufacture, in combination with a flexible backing, a homo- 15

geneous covering of various colors, the material of one color being spread completely over one side of the backing and having its exposed surface deeply indented with cuts imitating in the aggregate the grain of wood, the 20 material of different color being run therewith and allowed to harden and become physically integral therewith, substantially as described.

In testimony whereof, I, sign this specification in the presence of two witnesses.

THOMAS T. HOLLINGER.
